22 27 8 10 INVENTOR,
John S. Herbert.
By Martin O'Ferrall, Atty.

UNITED STATES PATENT OFFICE.

JOHN S. HERBERT, OF LOS ANGELES, CALIFORNIA.

WASHING MACHINE.

Application filed October 21, 1922. Serial No. 595,890.

To all whom it may concern:

Be it known that I, JOHN S. HERBERT, a citizen of the United States, residing at Los Angeles, in the county of Los Angeles and State of California, have invented new and useful Improvements in Washing Machines, of which the following is a specification.

My invention relates to washing machines of the power driven type, the principal objects of my invention being to provide a washing machine that is of relatively simple structure, capable of being easily and cheaply produced and which may be operated with comparatively little cost.

Further objects of my invention are, to provide a washing machine wherein the clothes or contents of the machine are thoroughly washed with a minimum loss of energy from the power required to operate the machine, further to provide a machine wherein the clothes to be washed are always maintained beneath the surface of the wash water and forced thereagainst as the clothes container rocks or swings to and fro with a cradle-like motion; further, to provide a construction wherein the cradle or clothes container may be easily and quickly elevated so as to lift the clothes entirely out of the wash water so that they may adequately drain before being passed through the wringer; further to provide simple and efficient driving means for the washing machine and the wringer that is associated therewith, and further, to provide simple means for effectively heating the wash water used in the tank or tub of the machine.

With the foregoing and other objects in view, my invention consists in certain novel features of construction and arrangement of parts that will be hereinafter more fully described and claimed and illustrated in the accompanying drawings in which:

Fig. 1 is a top plan view of my improved washing machine with parts broken away and in section.

Fig. 2 is a front elevational view of the machine.

Fig. 3 is an end elevational view of the machine, with the cradle or clothes container in elevated position.

Fig. 4 is a fragmentary end elevational view, showing a part of the driving mechanism.

Fig. 5 is an enlarged detail section of a

locking device that is effective in retaining the clothes container in elevated position.

Fig. 6 is a section taken on the line 6—6 of Fig. 5.

Fig. 7 is vertical section taken lengthwise through the center of the cradle or clothes container.

Fig. 8 is a cross section taken on the line 8—8 of Fig. 7.

Referring by numerals to the accompanying drawings which illustrate a practical embodiment of my invention, 10 designates a tank or tub of sheet metal, that is adapted to contain the wash water and said tank being supported in a suitable frame-work 70 that includes four corner posts 11, a front panel 12, rear panel 13 and end panels 14.

The tank 10 and water contained therein may be heated in any suitable manner, preferably, by two or more gas or oil burners 75 such as 15.

Secured to and projecting upwardly from the left hand end panel 14 is a wringer 16, of the type usually employed in household laundry operations.

The rear panel 13 is divided lengthwise to form two parts, the upper one of which is connected by hinges 17 to the lower part and secured to the upper edge of the upper part is the rear end of a lid or cover 18 85 that is adapted to entirely close to top of tub or tank 10.

When this lid or cover is closed it may be secured in such position by suitable latches 19 that are arranged on the upper portion 90 of front panel 12.

Suspended for swinging movement from lid or cover 18, by means of substantially U-shaped hangers 20 is a cradle or clothes receptacle 21 preferably formed of sheet 95 metal and having end walls 22 formed of wire screen. The front of this cradle is provided with a hinged or bodily removable door or panel 23, which, when open, permits the clothes to be readily placed within or removed from the cradle.

Depending from the top of the cradle is a series of transversely disposed ribs or bars 24 having rounded lower edges 25, and formed in each rib is a series of apertures 26.

Projecting upwardly from the bottom of the cradle is a series of transversely disposed ribs or bars 27 that are substantially inverted V-shaped in cross section.

The ribs 24 and 27 co-operate to hold the 110

clothes in the central portion of the chamber within the cradle and to rub against said clothes as the latter move to and fro while the machine is in operation.

Arranged on a suitable support in the rear lower portion of the machine frame is an electric motor 28, the shaft 29 of which is geared, preferably by a worm 30, and worm wheel 31, to the lower portion of a vertical shaft 32.

The upper end of this shaft 32 terminates within a gear box 33 that is arranged on top of the rear portion of a panel 34, that is secured on top of the left hand portion of the machine frame and which occupies the same horizontal plane with lid or cover 18 when the latter is closed.

Secured to shaft 32 within the gear box 33 is a pinion 35 that meshes with a pinion 36 that is journaled within said gear box and the toothed edge of said pinion overlies the inner edge of the panel 34.

Arranged on the left hand portion of lid or cover 18 is a gear box 37 that encloses a pinion 38, which latter meshes with pinion 36. Pinion 38 is secured to the upper end of a shaft 39 that is journaled in cover 18 and fixed to the lower end of said shaft is a short crank 40.

Pivots connected to crank 40 is one end of a pitman 41, the opposite end thereof being connected to a wrist pin 42 that projects upward from the top of cradle 21.

Shaft 32 extends upward into a housing 43 that encloses suitable gearing that may be controlled to connect said shaft to a wringer operating shaft 44.

Hinged to the upper edge and right hand end of the upper part of panel 13 is the rear end of a panel 45 that normally lies along the right hand edge of the machine frame in the same horizontal plane with the cover 18 when the latter is closed and the front end of said panel 45 is bevelled on its under side as designated by 46. This bevelled edge normally rests on a corresponding bevelled edge 47 that is formed on the upper edge of the right hand end of front panel 12.

Pivots connected to the forward portion of panel 45 is the upper end of a rod 48, the lower end of which is pivotally connected to a pedal lever 49, the rear end of which is pivotally connected to the rear lower portion of the machine frame.

The front end of this lever terminates in a foot plate 50.

Hinged to the intermediate portion of panel 45 is the upper end of a link 51, the lower end thereof being hinged to the intermediate portion of the front, right hand one of the posts 11.

A portion of the underside of panel 45 near its rear end and inner edge is cut away to form a recess 52 and pivotally mounted

at its rear end therein is a gravity latch 53, the front end of which is adapted to bear against a shoulder 54 that is formed on the upper end of the adjacent corner post 11 when the lid or cover 18 is swung upward to lift the cradle from the tub or tank as shown in Fig. 3 (see Fig. 5).

The operation of my improved washing machine is as follows:

Motor 28 drives shaft 29 and through worm 30 and pinion 31, shaft 32 is driven. Pinion 35 on shaft 32 transmits motion to shaft 39 through pinions 36 and 38 and through crank 40 and pitman 41, the cradle 21 is rocked to and fro within tub or tank 10.

The wash water within the tank is heated and maintained in heated condition by heat from the lighted burners 15. As the cradle is thus rocked the clothes therein will be constantly agitated and moved to and fro through the wash water while wholly submerged therein and during such action the clothes will to a certain extent engage with rubbing action against the ribs or rails 24 and 27. As a result of this rocking movement of the clothes beneath the surface of the water, said clothes will, within a relatively short period of time, be very thoroughly cleansed.

To lift the cradle so as to permit the clothes to drain and to enable them to be readily removed without necessitating the placing of the hands in the hot water, foot pressure is applied to the front end of lever 49 and the latter is forced downward to the position shown in Fig. 3. Such movement causes the bevelled edge 46 of panel 45 to ride down bevelled surface 47, and at the same time said panel will shift bodily rearward as a result of the rearward swinging movement of the upper end of link 51.

As these movements continue, the upper part of panel 13 to which the rear end of panel 45 is hinged, will swing rearwardly and downwardly, thereby swinging the front edge of top or cover 18 upwardly and rearwardly to the position shown in Fig. 3, and consequently lifting the cradle and clothes therein above the surface of the water in tank 10.

Front cover 23 may now be removed so as to give ready access to the washed clothes in the cradle and as soon as said clothes have drained and cooled, they may be removed and passed between the rolls of wringer 16 and which latter is driven from the motor through shaft 44.

When the cover and cradle are elevated as just described they will be retained in such position by gravity latch 53, for, as panel 45 moves to its rearward limit of movement, the front end of said latch will ride over and drop behind shoulder 54, thereby retaining the parts in elevated position. The

latch may be lifted from its locking position by pulling upward upon a pin 53^a that projects upwardly from the forward portion of said latch.

5 The apertures 26 in the rails or ribs 24 permits the upper strata of water to surge to and fro through the upper portion of the cradle while the latter is in motion, thereby materially increasing the speed or rapidity 10 with which the clothes are washed.

A washing machine of my improved construction is comparatively simple in structure, may be easily and cheaply produced, requires relatively little power in its operation, 15 accomplishes its work in very little time due to the fact that during the cleansing operation, all of the clothes are wholly submerged beneath the surface of the wash water, and the cradle or clothes container 20 may be very easily and quickly elevated, to permit the washed clothes to drain and to be readily removed and delivered to the conveniently located wringer.

Obviously the details of construction of 25 my improved washing machine may be slightly changed or modified without departing from the spirit of my invention, the scope of which is set forth in the appended claims.

30 I claim as my invention:

1. In a washing machine, a container for wash water, a hinged cover therefor, and a clothes receptacle suspended for swinging movement from said hinged cover.

35 2. In a washing machine, a container for

wash water, a hinged cover therefor, a clothes receptacle suspended for swinging movement from said hinged cover, and means for swinging said hinged cover upwardly to lift said receptacle from said 40 container.

3. In a washing machine, a container for wash water, a hinged cover therefor, a cradle suspended for swinging movement from said cover, said cradle having reticulated end 45 walls and clothes engaging members within said cradle on the top and bottom thereof.

4. In a washing machine, a container for wash water, a hinged cover for said container, a clothes receptacle suspended from 50 said cover for swinging movement within said container and pedally actuated means for swinging said cover upwardly to lift said receptacle from said container.

5. In a washing machine, a container for wash water, a hinged cover for said container, a clothes receptacle suspended from 55 said cover for swinging movement within said container, means for swinging said hinged cover upwardly to lift said receptacle 60 from said container and means for holding said cover in raised position.

6. In a washing machine, a container for wash water, a hinged cover therefor, a cradle suspended from said cover for swinging 65 movement within said container and said cradle having reticulated end walls.

In testimony whereof I have signed my name to this specification.

JOHN S. HERBERT.
